UNITED STATES PATENT OFFICE.

WILLIS C. SWIFT, OF COSHOCOTON, OHIO.

METHOD OF AND MEANS FOR MAKING AND ERECTING CONCRETE OR OTHER WALLS FOR BUILDINGS.

1,179,678.

Specification of Letters Patent. Patented Apr. 18, 1916.

Application filed April 13, 1911. Serial No. 620,783.

To all whom it may concern:

Be it known that I, WILLIS C. SWIFT, a citizen of the United States, residing at Coshocton, county of Coshocton, and State 5 of Ohio, have made a certain new and useful Invention in Methods of and Means for Making and Erecting Concrete or other Walls for Buildings, of which the following is a specification.

10 This invention relates to the method of and means for making and erecting concrete or other walls for buildings, and the object is to provide a method of producing or erecting walls or wall sections when made of 15 concrete or other suitable material, wherein the wall is formed or constructed in horizontal position at an elevation above the foundation upon which it is to rest, and in such relation with reference to the foundation 20 as to be lowered upon the foundation and into vertical position with expedition, without imposing unnecessary strains and stresses thereon during the setting of the same in vertical position upon the foundation, and with the expenditure of minimum 25 power in effecting the setting of the finished wall in vertical position upon the foundation.

In the patent to Aiken No. 889,083, is set 30 forth a method wherein the walls of buildings are formed in a horizontal position, with the window and door openings formed therein, the wall or wall sections being formed on the ground adjacent the foundation. After the wall is finished in its horizontal 35 position it is raised into vertical position to be set upon its foundation by tilting up the outer edge of the finished and formed wall so as to raise the same into vertical 40 position, and to set it upon the foundation.

In my pending application Serial No. 553,613, I have set forth, described and claimed a method wherein the wall or wall sections is formed horizontally on a suitable 45 support or mold frame, placed on the ground adjacent the foundation on which the wall is to be finally erected into vertical position, and then raising the edge of the finished wall which lies next adjacent to 50 and parallel with the foundation so as to bring the wall into vertical position and to set the same in that position upon the foundation. By this method the advantage is secured of enabling me to finish and suitably 55 decorate that surface of the wall which is

to form the outer surface of the building when the wall is erected, while the wall is in horizontal position and being formed, such surface in that case being the uppermost surface of the wall, when the wall sections 60 are formed without the foundation lines, where there is usually sufficient space in which to form simultaneously all the wall sections for one story.

The present invention relates to methods 65 of wall construction and erection of this class and nature, and the particular object in view is to avoid the necessity for employing hoisting apparatus required for raising the finished walls or wall sections 70 from the ground, and from horizontal position on the ground, into vertical position to be set on the wall, while at the same time retaining the advantageous feature of forming the wall in horizontal position with the 75 surface thereof which is to form the outer surface of the erected wall uppermost.

In carrying out my invention I propose 80 to employ a suitable elevated platform or framework, suitably supported at a convenient height above the foundation, and in horizontal position while the wall is being molded or formed thereon, and I propose to support said platform at one end upon 85 shoes or rollers arranged to operate on elevated trackways, this end of the platform being the end farthest removed from vertical position over the foundation. I also propose to support the platform at the end or edge thereof lying approximately vertically 90 above and parallel with the foundation, by suitable means, which, when the wall has been completed in its horizontal position, may be released to permit said edge or end of the platform and the formed 95 wall carried thereby to be lowered from its elevated point, so as to bring the formed wall into vertical position directly over and to seat the same in that position upon the foundation, the outer or remote end or edge 100 of the finished wall and its supporting platform progressing or moving along the elevated trackways which support them, and toward a position to bring the finished wall and its support into proper relation for the 105 finished wall to be set upon the foundation. This constitutes my present invention, and by reason thereof I am enabled to form the wall in horizontal position, and therefore in 110 the position in which the wall can be most

105
110

readily, easily, and conveniently formed, particularly when made of concrete, cement or other suitable plastic material. I am also enabled to suitably decorate the uppermost surface of the wall if formed within the foundation lines while being formed in its horizontal position so as to properly finish the surface thereof to form the outermost surface of the wall when erected upon the foundation and vice versa if formed without the foundation lines. I am also enabled to avoid the use of elevating machinery as gravity is utilized to effect the lowering of the finished wall from its horizontal into its vertical position and the setting of the same upon the foundation. By this method I am also enabled to avoid imposing unnecessary and undue strains and stresses upon the finished wall as the rear edge being mounted on rollers the wall is free to twist and thereby automatically maintain the even distribution of weight on each support, while being set upon its foundation. This is an important and material matter when it is considered that these walls or wall sections when formed and with the reinforcements which are sometimes embedded therein while they are being formed, as well as the concrete or cement itself forming the wall aggregate a very great weight, which tend to cause injury to the wall while being elevated, besides requiring powerful machinery to effect the elevation thereof.

35 The method involved in my present invention may be carried out in many specifically different ways, and by many specifically different constructions of apparatus.

In the accompanying drawing I have shown a simple arrangement of apparatus which is effective for the purpose, but my invention in its broadest scope, and the method which it embodies, as defined in the claims, is not to be limited or restricted to the use of this particular construction and arrangement.

In the drawing.—Figure 1 is a top plan view, somewhat diagrammatic of an elevated platform or frame, showing a wall section formed thereon, the platform being shown in horizontal position. Fig. 2 is a front elevation of the same, showing in dotted lines the wall section lowered into vertical position and set upon its foundation. Fig. 3 is a side elevation of the same, also indicating in dotted lines the vertical position of the wall when lowered and set upon its foundation.

In the drawing, 5, is a wall foundation for a building. Adjacent the wall foundation is erected a framework which may have any suitable construction. In the form indicated in the drawing this framework comprises end parts spaced a distance apart corresponding to the horizontal dimension of

the wall or wall section to be formed, and each comprising uprights 6, braces 7, and a top bar 8, the latter constituting a track. The track members 8, extend in parallel relation with respect to each other and in transverse direction with reference to the foundation 5, which is to receive the wall when completed, said tracks terminating at one end approximately over and elevated above the portion of the foundation which is to receive the wall. The side members 9, of a frame work, mold or platform, are provided at their outer end with gudgeons 10, designed to operate on and along the track bars 8, and to support the mold or platform at its outer end when in horizontal position. The side members 9, of the mold frame or platform, are connected together at their ends by means of the end pieces 11, 12. This mold or platform frame is designed to receive and support a suitable flooring upon which the wall, or wall section is to be formed.

As above indicated this mold frame or platform is supported at its outer end by the rollers or shoes 10, resting upon the track members or bars 8. At its other end the mold frame or platform is supported, preferably at each corner by means of chains, ropes or other suitable or convenient flexible devices 13, secured at one end to bracket pieces, 14, and extending therefrom and coiled upon short shafts 15, suitably journaled in bearings formed on the supporting framework 6, 7. The shafts 15, are provided with worm gears 16, meshing with and driven by similar worm gears 17, carried upon a shaft 18, extending between the frames 6, and journaled in bearings 20, carried thereby. This shaft 18, is equipped with a hand wheel 19, by means of which it may be rotated, so as to impart rotation to the gears 16 and shafts 15.

From the foregoing description it will be seen that the mold or platform on which the wall or wall sections is formed is a rocking or swinging platform, being held or supported at one end upon the shoes or rollers on an elevated track system, and supported at its other end by chains or cables adapted to be wound upon shafts, the latter being turned through suitable worm gearing, in order to raise and support the platform in horizontal position for the wall or wall sections to be formed therein or thereon. After the wall section is formed and completed, and has sufficiently set or hardened, and is ready to be erected on its foundation, the shafts on which the supporting chains or cables are wound are rotated so as to permit the edge of the wall which lies vertically above the foundation which is to receive it, to be lowered. As this edge of the wall and its platform are lowered the other edge or end of the platform which is sup-

ported upon the rollers or shoes, progresses along the trackways toward the front ends thereof, thereby bringing the wall from its horizontal into vertical position directly 5 over the foundation which is to receive it, and finally depositing the wall upon said foundation.

If desired and in order to lower the wall onto its seat on the foundation, after it has 10 attained vertical position, the tracks 8, may be beveled off at their outer ends, or pockets or depressions formed therein as indicated at 22, into which the rollers or shoes 10 may ride, as the platform and wall approach 15 vertical position, thereby enabling the platform and wall carried thereby to be lowered sufficiently for the wall to be received at its lower edge in the ground or seat formed to receive the same in the foundation.

20 It is obvious that the wall may be retained upon its supporting platform in any suitable or convenient manner during the time the said wall is being lowered into position to be received vertically upon the foundation, and when so received, to be released 25 from the platform so that the latter may be removed. At some time before the platform and wall are lowered or moved into vertical position the platform frame bar 12, may be 30 removed to facilitate the depositing of the wall from the platform onto the foundation.

From the foregoing description it will be seen that I provide a simple and efficient method of forming and erecting concrete or 35 other walls, wherein the wall is formed in horizontal position with the side thereof, preferably, uppermost so as to be finished off to form the outermost surface of the wall when erected in vertical position upon its 40 foundation, and wherein the wall, so formed, may be readily shifted or moved by gravity into vertical position and deposited in that position upon the foundation, thereby requiring no expenditure of 45 power to accomplish this work, and without imposing any unnecessary strains or stresses upon the formed wall.

Having now set forth the object and nature of my invention and a method of carrying 50 the same into practical operation, what I claim as new and useful and of my own invention, and desire to secure by Letters Patent, is,—

1. The method of constructing and erecting 55 the walls of buildings which consists in forming a wall in a substantially horizontal position, with the edge thereof which is to be received on the wall foundation arranged in line with and vertically above the seat on the foundation which is to receive it, and at 60 an elevation thereover, substantially the same as the height of the wall when erected and then lowering said edge by gravity into position to be received permanently on the 65 foundation, the lowering movement of said

inner edge causing the outer edge of the formed wall to simultaneously move forwardly into position over the foundation to bring the wall into vertical position.

2. The method of constructing and erecting 70 the walls of buildings which consists in forming the wall in a substantially horizontal position at an elevation above the permanent foundation which is to receive the wall, with the edge of the wall which is to be received permanently on the foundation arranged lying parallel with and substantially vertically over the foundation seat, at a height substantially the same as that of the wall when erected and then lowering 75 said edge, the lowering movement of such edge causing the other edge of the formed wall to progressively move rectilinearly so as to shift the wall from horizontal into 80 vertical position to be received upon the 85 foundation.

3. The method of constructing and erecting 90 the walls of buildings which consists in forming the wall in a substantially horizontal position at an elevation above the permanent foundation which is to receive it, substantially that height of the wall when erected with the edge of the wall which is to be received permanently on the foundation lying substantially parallel with 95 and vertically above the foundation, and then lowering said edge the lowering movement of said edge being effected by gravity and causing the opposite edge of the formed wall horizontally to simultaneously move 100 forward toward position vertically over the foundation, so as to bring the formed wall into vertical position to be received upon the foundation.

4. The method of constructing and erecting 105 the walls of buildings which consists in forming the wall in a substantially horizontal position at an elevation above the permanent foundation which is to receive the same, substantially the height of the wall when erected with the edge of the wall which is to be received permanently on the foundation lying substantially parallel with 110 and vertically above the foundation, then lowering said edge by gravity, said lowering movement causing the opposite edge of the formed wall to move horizontally forward toward position vertically over the foundation, so as to bring the formed wall into vertical position, and then lowering 115 the formed wall vertically to its seat on the foundation.

5. The combination with a permanent wall foundation, of a framework adjacent thereto and extending horizontally above the same, a platform supported at one end upon the framework, suspending devices mounted on the framework for supporting the other end of the platform, said platform forming a mold or frame upon which a wall is 120 125 130

to be constructed, the suspended end of the platform lying parallel with and vertically above the foundation wall, and means for lowering the suspended end of the platform to deposit the formed wall upon the foundation, the lowering of the suspended end causing the remote end to advance into position vertically over the foundation.

6. The combination with a permanent wall foundation, of a horizontal elevated framework, a platform arranged to be supported at one end movably upon the elevated framework, suspension cables for suspending the other end of the platform, the cable suspended end of the platform being arranged vertically over and parallel with the foundation, and means for releasing the cable suspension to permit the suspended end of the platform to descend and the supported end to move horizontally forward into vertical position over the foundation.

7. The combination with a permanent wall foundation, of an elevated framework, having horizontal track ways, a platform having at one end means to rest on and to move along said horizontal track ways, suspension cables for supporting the other end of the platform, the cable suspended end of the platform lying parallel with and vertically over the foundation, and means for releasing the cable suspension of the platform to permit the suspended edge thereof to be lowered and the track sup-

ported edge to move horizontally along the trackway, to bring the platform into vertical position over the foundation.

8. The combination with a permanent wall foundation, of an elevated framework having horizontal track ways, a platform, rollers carried thereby arranged to rest on and to move along the trackways, said rollers forming a support for one end of the platform, cable suspending devices for supporting the other end of the platform, the cable suspended end of the platform lying parallel with and vertically over the foundation wall at a height approximately corresponding to that of the wall when erected, means for releasing the cable suspended end of the platform to permit the suspended end thereof to be lowered and the track supported end to move horizontally along the trackway to bring the platform into vertical position over the foundation, the ends of the trackways which lie over the foundation having seats or depressions therein, to permit the platform to be lowered vertically as it reaches vertical position.

In testimony whereof I have hereunto set my hand in the presence of the subscribing witnesses, on this 13th day of February A. D., 1911.
